UNITED STATES PATENT OFFICE.

FRANK H. WILLIAMS, OF BUFFALO, NEW YORK.

GRAB-BUCKET.

1,376,847.

Specification of Letters Patent.

Patented May 3, 1921.

Application filed August 17, 1916. Serial No. 115,123.

To all whom it may concern:

Be it known that I, FRANK H. WILLIAMS, a citizen of the United States of America, residing at Buffalo, county of Erie, and 5 State of New York, have invented certain new and useful Improvements in Grab-Buckets, of which the following is a full, clear, and exact description.

My invention relates generally to buckets 10 and more particularly to that type of bucket which is used in the handling of sand, gravel or ore.

It is well known to those skilled in the art, that the buckets of the prior art are 15 frequently constructed with two long links which extend from the bucket segments up to the upper sheaves. This construction requires that a good deal of head room be provided for the bucket and such a bucket 20 has small or insufficient power when closing.

In my invention I have sought to overcome these disadvantages by providing a bucket so designed and constructed as to do away with the long links above mentioned 25 and to make a bucket so compact in its construction that comparatively little head room is required, and also one in which the closing power is greater than in the type of bucket referred to.

Another object has been to provide a 30 bucket in which simple and effective means is provided for keeping the lower sheave casting in parallel relation throughout its motion.

Moreover, in my device, I have provided 35 novel and effective means for keeping the bucket segments substantially equidistant from the center plane of the bucket, which plane is the vertical plane passing through 40 the center of the girders and with which the contacting surfaces of the bucket segments, when closed, are substantially coincident.

My bucket is designed with a number of 45 girders across the top, which, when the bucket segments are fully opened, form with the intermediate parts a solid, non-pivotal contact, so that a very strong and durable construction is provided, which will resist 50 the shock resulting from the dropping of the bucket on to any surface supporting the material being handled. These girders also transmit the pressure due to the pull of the ropes to points near the outer extremities 55 of the segments and exert this pressure in substantially a vertical direction.

Furthermore, all the sheaves and other working parts of my bucket are so inclosed and positioned that none of the material being handled can get into the bearings and 60 cause undue wear.

A further object has been to provide a 65 novel arrangement of the sheaves so that an equalizing reaving of the closing rope is had.

The above objects and advantages have been accomplished by the device shown in the accompanying drawings, in which:

Figure 1 shows a side elevation of my 70 bucket.

Fig. 2 is an end elevation thereof.

Fig. 3 is a sectional elevation taken on line 3—3 of Fig. 1.

Fig. 4 is an enlarged, plan view of the 75 upper portion of the bucket with the bucket segments removed.

Fig. 5 is a fragmentary, plan view of the 80 bucket segments and the uncovered, lower sheave casing, and is viewed from line 5—5 of Fig. 1.

Fig. 6 is a fragmentary, sectional view, 85 showing one corner of one of the bucket segments and is taken on line 6—6 of Fig. 1.

Fig. 7 is an enlarged, perspective view of 90 one of the hinge links of my bucket.

Fig. 8 is a fragmentary, sectional view showing the stops on one of the girders, and 95 is taken on line 8—8 of Fig. 1.

Fig. 9 is a side elevation of the bucket 100 shown in Fig. 1 in its open position and shows in the dotted lines the position of the parts in its partly opened position.

Fig. 10 is a fragmentary, side elevation 105 showing the position occupied by the stops when the bucket parts are in a certain degree of opening.

Fig. 11 is a side elevation of a bucket having a modified form of equalizing means.

Fig. 12 is a fragmentary, sectional view 110 through one of the trunnion pins for the bucket segments and is taken on line 12—12 of Fig. 11.

Referring now to the drawings and more particularly to Figs. 1 to 10, inclusive, 20 and 21 are the bucket segments which are 105 of the usual plate construction and are provided at their upper adjacent edges with trunnion plates 22 and 23, respectively. 24 is the lower sheave casing which is disposed between the trunnion plates. This sheave 110 casing is provided at each end and on opposite sides with lugs 25 (Fig. 12). These

lugs are provided with central apertures 26 in which are disposed trunnion pins 27 and 27^a. The trunnion plates 22 and 23 are provided with suitable bearings arranged to 5 engage with the trunnion pins 27 and 27^a, respectively, whereby the bucket segments are pivotally connected with the lower sheave casing 24. This construction thus provides pivotal connections between the 10 bucket segments which throughout the travel of the said segments remain at a constant distance from each other. The trunnion plates 22 each have an offset or arm 28 which extends inwardly and downwardly at 15 a certain angle, and the trunnion plates 23 are each also provided with an arm 29 which extends upwardly and inwardly at a certain angle. A pivot pin 67 is provided on the arm 28 and a pivot pin 68 is provided on 20 the arm 29. An equalizer link 30 is arranged on each side of each of the arms 28 and 29 and pivotally attached to the pins 67 and 68, thereby connecting these arms and the plates of which they form a part. 25 The angle of the arms 28 and 29 is such that, together with the connecting, equalizing links 30, an equal rotation is given to each of the bucket segments and an equal velocity of rotation to both segments in reverse directions. This I have found, is only true when the parts have a certain relation as that set forth in the following formula, 30 which I have evolved:—

$$R = .7934 D.$$

35 $C = R \text{ Sine } 41\frac{1}{2}^\circ$ (or greater).

Where

R=the radius of the arms 28 and 29.

D=one-half the distance between the axes of the pivot pins 27 and 27^a.

40 C=the distance between the vertical plane passing through the axis of the trunnion pin 27^a and the axis of the pin 68, and also represents the distance between the horizontal plane passing through the trunnion pin 27 and the axis of the pivot pin 67, 45 when the bucket segments are in their normally-closed positions.

This construction thus provides a simple, 50 cheap and effective equalizing connection for keeping the lower sheave block in parallel relation throughout its travel.

Above the bucket and at each side is provided an arc-shaped head girder 31. Each 55 of these girders is preferably formed of a flat web 32 having secured to its outer face and at the upper and lower edges thereof an angle iron 33. The girders are arranged each at one side of the bucket and between 60 their lower edges are secured the hinge members 34. When the hinge member is riveted or otherwise secured to the girder, a stop 35 is also secured, preferably by the same means, in the corner of each end of 65 the angle irons 33, which stops will be here-

inafter more fully described. Each hinge member 34 has at each end an outwardly extending bearing lug 36 and passing through these lugs is a hinge pin 37. 70 38 are the hinge links, each of which is pivotally secured at its lower end 39 to one corner of one of the bucket segments. The end 39 of the link is connected with a pin 40 passing through the corner of the bucket segment and through the hinge bearing 41 75 secured thereto. This hinge bearing is provided with a stop 47 to be hereinafter referred to. Each hinge link (Fig. 7) is provided at its upper end with two oppositely arranged bearing lugs 42 and 43, thus providing a space 44 therebetween. The bearing lugs 36 of the hinge member 34 are arranged in the space 44 of the hinge links and between the bearing lugs 42 and 43. The hinge pin 37 of each hinge member 80 passes through the bearing lugs 42 and 43 of the hinge link and is preferably secured thereto by a cotter pin or other suitable means. A stop shoulder 45 is provided on each hinge link 42 and these stop shoulders 85 are so arranged that they will contact with the outer reinforced edges of the bucket segments when the bucket is in its open position, thereby giving a solid, positive stop for the rotative action of the segments. 90 Projecting from the bearing lug 43 of each of the links is an inwardly extending stop lug 46, which is arranged, when the bucket is being opened or closed to move between the stops 35 secured to the head girders 100 and thereby limit the oscillation of the links and keep the lower sheave casing 24 moving in a substantially straight line. When the stop lugs 46 are in the middle or neutral position shown in Fig. 10 the side of 105 the hinge links will contact with the stop 47, provided on the hinge bearing 41 and will thus keep the lower sheave casing moving in a substantially straight line while passing through the position shown in this 110 figure and in which position the stop lugs 46 are out of contact with the lugs 35.

The sheave casing 24 is provided with two casing sheave pins 48, which support casing sheaves 49 and 50. The sheave 115 pins 48 are so arranged that the planes through which the casing sheaves 49 and 50 rotate make a small acute angle with the vertical center plane of the bucket and preferably these casing sheaves overlap as shown in Figs. 3 and 5. A cover 51 is provided for the sheave casing, so as to exclude all dirt therefrom. This cover is provided with suitable openings for the passage of the ropes which engage with the 120 sheaves.

Supported between the girders 31, and arranged on each side of the center thereof, are two sheave supports 52. These supports are arranged in interspaced relation 125

and a girder sheave 53 is arranged therebetween and mounted upon a pin 54. A pin 55 passes through the sheave supports and provides an anchor for the 5 end of the hoisting rope 56. Another pin 57 is provided near the top of the sheave supports and serves as an anchor for the hold rope 58, and also as a support for the closing rope guide 59. 60 10 are braces which extend preferably from the point of junction of the sheave supports with the girders to the center of the hinge members 34. The hold rope 58 is secured at its lower end to the pin 57 and the hoisting rope 56 is passed through the guide 59, around the casing sheave 50 up and over the girder sheave 53 arranged between the sheave supports, down around the casing sheave 49 and up to the pin 55 where it is 15 20 anchored. This construction provides a symmetrical arrangement and pull on the ropes.

In the modified form of bucket shown in Figs. 11 and 12, the bucket segments 61 and 62 have secured at their upper adjacent edges the trunnion plates 63 and 64. These trunnion plates are rotatably secured to the pivotal pins 27 and 27^a carried by the lower sheave casing 24 in the same manner as the 25 30 form just above described. The plates 63 and 64 have their adjacent surfaces provided with gear segments 65 and 66, respectively. These gear segments are in mesh with each other and when the bucket 35 is opened they keep the lower sheave casing 24 in parallel relation and thus perform the same function as the links 30 in the form above described.

When the bucket shown in Figs. 1 to 10, 40 inclusive, is closed as shown in Fig. 1, it will be seen that the stop lugs 46 of the hinge links 38 are in contact with the upper stops 35 carried by the head girder. In this position these lugs will prevent the bucket segments from moving sidewise or the lower sheave casing from getting out of alignment with the sheave supports. When the bucket is opened and the trunnion pins 27 and 27^a move downwardly until 45 50 55 they lie in the same horizontal plane as the hinge pins 37, these pins 27 and 27^a, respectively, and 37 will be at their minimum distance from each other. When in this position the stop lugs 46 will be in their neutral position (Fig. 10). When in this position the stops 47 carried by the hinge bearing 41 will contact with the hinge links 38 and keep the lower sheave block 24 in alignment. As the trunnion pins 27 and 27^a 60 65 continue to move downwardly until they occupy the same horizontal plane as the pins 40 at the lower ends of the hinge links 38, the pins 40 will be at their maximum distance, in which position the stop lugs 46 of the hinge links will be in contact

with the lower stops 35 of the head girder (as shown in dotted lines in Fig. 9). During the balance of travel of the trunnion pins 27 and 27^a the pins 40 will be drawn inwardly to their minimum distance thereby rotating 70 the hinge links 38 and moving the stop lugs in contact with the upper stop 35 carried by the girder or in the same position as those shown in Figs. 1 and 9.

It will thus be seen that the bucket segments and parts connected therewith will be kept substantially equidistant from the center of the head girder throughout the movement of opening or closing the bucket and thus provide a substantially straight 75 80 line motion for the lower sheave casing 24.

This hinge link is also used in the modified bucket shown in Figs. 11 and 12 and its operation need not, therefore, again be described.

The lower sheave casing 24 in the buckets shown in Figs. 1 to 10, inclusive, is held non-rotative by means of the links 30. In the form shown in Fig. 11 this function is performed by the gear segments 65 90 95 and 66.

Obviously some modifications of the details herein shown and described may be made without departing from the spirit of my invention or the scope of the appended 95 claims and I do not, therefore, wish to be limited to the exact embodiment herein shown and described.

Having thus described my invention, what I claim is:

1. A grab bucket comprising bucket segments, the bucket segments being pivotally mounted at points which remain equidistant from each other throughout their travel, a plurality of girders disposed across 105 the top of the segments and extending near to the outside edges thereof, hinge links connecting the outer ends of the girders with the outer edges of the segments, said links having their lower ends pivotally 110 united to said segments, stops carried by the girders, and stops carried by the bucket segments, both said stops being engageable by said hinge links whereby the lower ends of opposite hinge links will remain substantially equidistant from the vertical central plane of the bucket throughout their travel.

2. A grab bucket comprising bucket segments, the bucket segments being pivotally 120 mounted at points which remain equidistant from each other throughout their travel, a plurality of girders disposed across the top of the segments and extending near to the outside edges thereof, hinge links connecting 125 the outer ends of the girders with the outer edges of the segments, said links having their lower ends pivotally united to said segments, fixed stops engageable by said links, when the bucket assumes its maximum 130

upper and lower positions, and a rotative stop for engaging the links when the bucket segments are in their intermediate positions, whereby the segments and the corresponding co-acting parts are kept substantially equidistant from the vertical center plane of the bucket throughout their travel.

3. A grab bucket comprising bucket segments, the segments being pivotally mounted at points which remain equidistant from each other throughout their travel, means connecting the segments at their pivotal points so that there is given to each of the segments equal rotation and to both of them an equal velocity of rotation in reverse directions, a plurality of girders disposed across the top of the segments and extending near to the outside edges thereof, and means located at the outer edges of the girders and bucket segments for keeping the bucket segments and the corresponding, co-acting parts equidistant from the vertical center plane of the bucket throughout their travel.

25 4. In a grab bucket, the combination with two bucket segments, of a member arranged between segments, trunnion pins carried by the member and passing through the segments, the trunnion pins being arranged at a fixed distance from each other, mechanical means for positively closing the bucket segments about their pivotal points, and equalizer links pivotally connecting the segments and so positioned that there is given to each of the segments a substantially equal rotation and to both of them a substantially equal velocity of rotation in reverse directions.

5. A grab bucket comprising pivotally mounted bucket segments, a girder disposed across the top of each side of said segments and extending near to the outside edges thereof, a hinge member extending between and secured to each of the two opposite girders, a pair of hinge links pivotally secured to each of said hinge members, said links having their lower ends pivotally united to said segments, and stops engageable by said hinge links, whereby the bucket segments and the corresponding co-acting parts are kept substantially equidistant from the vertical center plane of the bucket throughout their travel.

6. A grab bucket comprising bucket segments, a member arranged between said segments, trunnion pins for said segments carried by said member and arranged at a constant distance from each other, equalizing links pivotally connecting said segments, a girder disposed across the top of each side of said segments and extending near to the outside edges thereof, a hinge member extending between and secured to the ends of the two opposite girders, a pair of hinge links pivotally secured to each of said hinge

members, said links having their lower ends pivotally united to said segments, and stops engageable by said hinge links, whereby the bucket segments and the corresponding, co-acting parts are kept substantially equidistant from the vertical center plane of the bucket throughout their travel.

7. A grab bucket comprising pivotally mounted bucket segments, a plurality of girders disposed across the top of said segments and extending near to the outside edges thereof, a hinge member secured to each of the girders at each end thereof, a pair of hinge links pivotally secured to each of said hinge members, said links having their lower ends pivotally united to said segments, each of said links being provided at its upper end with a stop lug, and stops secured to said girders, said stops being engageable by said stop lugs, whereby the bucket segments and the corresponding, co-acting parts are kept substantially equidistant from the vertical center plane of the bucket throughout their travel.

8. A grab bucket comprising pivotally mounted bucket segments, a plurality of girders disposed across the top of said segments and extending near to the outside edges thereof, a hinge member secured to said girders at each end of said bucket, a pair of hinge links pivotally secured to each of said hinge members, said links having their lower ends pivotally united to said segments, each of said links being provided at the upper end with a stop shoulder, said shoulder being engageable by the outer edges of said segments when fully open, whereby a solid, positive stop is provided for the rotative action of the segments.

9. A grab bucket comprising pivotally mounted bucket segments, a plurality of girders disposed across the top of said segments and extending near to the outside edges thereof, a hinge member secured to said girders at each end of said bucket, a pair of hinge links pivotally secured to each of said hinge members, said links having their lower ends pivotally united to said segments, each of said links being provided at its upper end with a stop lug and a stop shoulder, stops secured to said girders, said stops being engageable by the said stop lugs and said shoulders being engageable with the outer edges of said segments when fully open, whereby a solid, positive stop is provided for the rotative action of the segments.

10. A grab bucket comprising pivotally mounted bucket segments, a girder disposed across the top of each side of said segments and extending near to the outside edges thereof, a hinge member extending across and secured to the ends of the two opposite girders, a pair of hinge links pivotally secured to each of said hinge members, each

of said links being provided at its upper end with a stop lug, stops secured to said girders and engageable by said stop lugs, a hinge bearing at each of the top outer corners of each of said segments, the lower end of each of said hinge links being pivotally united to one of said bearings, each of said bearings having a stop engageable with one of said links, whereby the bucket segments and the corresponding, co-acting parts are kept substantially equidistant from the vertical center plane of the bucket throughout their travel.

11. In a grab bucket, the combination with two bucket segments and a lower sheave casing secured to the bucket, of a girder secured across the top of each side of the segments, a girder sheave rotatably mounted in a plane parallel with the transverse vertical center plane of the bucket, and two casing sheaves rotatably mounted within the casing in planes which make small acute angles with the transverse center plane of the bucket, each of the casing sheaves being mounted upon a separate pin disposed on opposite sides of the longitudinal vertical center plane of the bucket.

12. In a grab bucket, the combination

with two bucket segments and a lower sheave casing secured to the bucket, of a girder secured across the top of each side of the segments, a girder sheave rotatably mounted in a plane parallel with the transverse vertical center plane of the bucket, two casing sheaves rotatably mounted within the casing in planes, which make small acute angles with the transverse center plane of the bucket, each of the casing sheaves being mounted upon a separate pin disposed on opposite sides of the longitudinal vertical center plane of the bucket, and a hoisting rope anchored to the girder, then passing downwardly around one of the casing sheaves, then upwardly around the girder sheave, then downwardly around the other of the casing sheaves and then upwardly through the center of the bucket, whereby a symmetrical arrangement and pull of the hoisting rope is provided.

In testimony whereof, I have hereunto signed my name in the presence of two subscribing witnesses.

FRANK H. WILLIAMS.
